UNITED STATES PATENT OFFICE

170,462

DECANTER

Robert E. Hennessy, Summit, N. J., assignor to
National Distillers Products Corporation, New
York, N. Y.

Application April 6, 1953, Serial No. 24,364

Term of patent 14 years

(Cl. D58—7)

To all whom it may concern:

Be it known that I, Robert E. Hennessy, a citizen of the United States, residing at Summit, in the county of Union and State of New Jersey, have invented a new, original, and ornamental Design for a Decanter, of which the following is a specification, reference being had to the accompanying drawing, forming a part thereof.

Fig. 1 is a side perspective view of a decanter, showing my new design;

Fig. 2 is a side face elevational view;

Fig. 3 is a side elevational view; and

Fig. 4 is a top plan view.

I claim:

The ornamental design for a decanter, as shown.

ROBERT E. HENNESSY.
